EMANUEL AUFIERO, OF BROOKLYN, NEW YORK, ASSIGNOR TO E. A. LABORATORIES, INC., OF BROOKLYN, NEW YORK, A CORPORATION OF NEW YORK.

SIGNAL FOR MOTOR VEHICLES.

1,414,613.

Specification of Letters Patent. Patented May 2, 1922.

Application filed February 26, 1921. Serial No. 448,089.

To all whom it may concern:

Be it known that I, EMANUEL AUFIERO, a citizen of the United States, residing at Brooklyn, in the county of Kings, State of New York, have invented certain new and useful Improvements in Signals for Motor Vehicles; and I do hereby declare the following to be a full, clear, and exact description of the invention, such as will enable others skilled in the art to which it appertains, to make and use the same.

My invention is an improvement in signals for motor vehicles, and relates to audible signals, of the character in which a diaphragm is rapidly vibrated to produce sound waves, by means of an electrically controlled motor.

An object of the invention is to provide in such a device, a simple inexpensive mounting for the motor in the form of an open top frame casing in which the sides and ends provide a frame for supporting the motor shaft, pole pieces and brush, and the bottom acts as a stay and brace, to hold the sides and the ends parallel and in proper position with respect to each other.

Another object is to provide a mounting of the character specified capable of being easily attached to the signal and detached therefrom, and carrying means for thoroughly lubricating the motor shaft over extended periods without attention, and wherein the shaft is so mounted that it may be actuated toward and from the diaphragm, to insure the proper engagement between the same and the diaphragm, and compensate for wear.

In the drawings, Figure 1 is a horizontal section through the signal and the hood; Figure 2 is a longitudinal section of the motor casing; Figure 3 is a section on the line 3-3 of Figure 2.

In the present embodiment of the invention, the signal comprises a diaphragm 1 which is held between the section 2 and 3 of a casing, the said sections being held together by screws 4. The section 2 of the casing is a washer and carries the amplifier or horn 5. The section 3 has a reduced portion 6 circular in cross section about which fits the open end of the cup shaped hood 7, which protects the motor and is connected to the section 3 of the diaphragm casing within the hood. The diaphragm

has a lug or tooth 8 centrally arranged and this tooth is adapted to be engaged by the teeth at the periphery of a disc 9 connected to the motor or armature shaft 10.

The motor, which is of any desired construction, comprising the armature shaft 10, the pole pieces 11, and the brushes 12, cooperating with the commutator 13, is supported by a frame having an open top, and comprising sides 14, ends 15 and a bottom 16. The ends 15 have openings for the motor shaft, and the pole pieces 11 have reduced portions 11^a, which are passed through openings in the sides 14, and are headed outside of the sides as shown, to hold the pole pieces in place. The brushes 12 are carried by supports 17 which are riveted to the sides 14 of the frame and are insulated therefrom as shown. The motor frame may be from suitable sheet metal, as for instance, steel of a suitable gauge, and the sides and ends provide a frame or support for the motor while the bottom acts as a stay and brace to hold the sides and ends parallel and in proper relation with respect to each other. At the end remote from the disc 9, the frame end 15 has a threaded opening larger than the armature shaft, and a nut 18 is threaded into this opening, the armature shaft passing through the nut. The nut is held in position with respect to the end by means of a locking nut 19, and the nut carries a washer 20, which is connected with the shaft in such manner as to constrain the shaft to move longitudinally with the nut while permitting the shaft to rotate freely with respect to the nut. This construction is shown and described in my copending application, Serial No. 448,088 of even date herewith.

The motor frame is connected to the diaphragm casing by means of a bar 21, which is connected to the section 3 of the signal casing, and to the end of the motor frame by screws 22. These screws are passed through registering openings in the diaphragm casing and in the bar, and have threaded engagement with the end of the motor frame. Means is also provided for insuring lubrication of the armature shaft without frequent attention on the part of the driver. The said means is in the form of oil cups 23 and 24, which are secured to the bar 21 and to the remote end 15 of the motor frame. These

5 cups extend on both sides of the shaft and above and below the same, so that when the shaft is in place, it is entirely surrounded by lubricant, and will be thoroughly lubricated over an extended period, without the necessity of further attention. Referring to Figures 2 and 3, it will be seen that the end 15 of the motor which is adjacent to the bar 21, has an opening of sufficient size to permit the passage of the oil cup, the said cups being plates which are riveted to the bar and the motor frame and have their central portion offset outwardly to provide the cups. The hood 7 is secured in place by means of 10 a screw 25 which passes through the end of the hood and engages a threaded opening in the adjacent end of the motor frame.

15 In assembling the improved signal, the motor, is first assembled in the frame. The 20 disc 9 is threaded onto the armature shaft and when the said disc is removed the shaft may be inserted through the opening in the bar 21, it being assumed that the section 3 of the diaphragm casing is detached to permit the assembling of the parts. The motor frame is now connected to the bar 21, and the section 3 of the diaphragm casing by means of the screw 22, and the disc is threaded onto the motor shaft. The section 3 is then 25 reconnected to the section 2 and the shaft 10 is adjusted to provide the proper engagement between the teeth of the disc and the lug 8. Afterward the hood may be replaced. Cast iron and castings of every sort are 30 eliminated in the improved motor support, the entire construction being of sheet metal.

35 I claim:

1. In a signal of the class described, the 40 combination with the diaphragm and casing therefor, of an electrically controlled motor for vibrating the diaphragm, said motor comprising a box-like sheet metal frame, an armature shaft perpendicular to said diaphragm, bearings on two opposite sides of 45 said frame for said shaft, an actuator for the diaphragm outside of said frame, pole pieces and brushes carried by the other two opposite sides of said frame and a web connecting the edges of said four sides.
2. In a signal of the class described, the 50 combination with the diaphragm and casing therefor, of an electrically controlled motor for vibrating the diaphragm, said motor comprising a box-like sheet metal frame, an 55 armature shaft perpendicular to said diaphragm, bearings on two opposite sides of said frame for said shaft, an actuator for the diaphragm outside of said frame, pole pieces and brushes carried by the other two 60 opposite sides of said frame, a web connecting the edges of said four sides, and a bar attached to the side of the frame adjacent

said diaphragm casing, said bar containing the bearing for the armature shaft.

3. In a signal of the class described, the 65 combination with the diaphragm and the casing therefor, of an electrically controlled motor for vibrating the diaphragm, said motor comprising a frame having an open top and having openings in the ends for the 70 motor shaft, the pole pieces and brushes being carried by the sides of the frame, and means for attaching the motor frame to the diaphragm casing, said means comprising a bar adapted to be arranged transversely of 75 the diaphragm casing, and a common means for connecting the bar to the diaphragm casing and to the adjacent end of the motor frame, said bar having a shaft bearing and carrying an oil cup through which the shaft 80 extends and the adjacent end of the motor frame having an opening for receiving the oil cup.

4. In a signal of the class described, the 85 combination with the diaphragm of a support therefor, and means for vibrating the diaphragm comprising an electric motor, said motor having its frame formed of a rectangular sheet metal piece with the armature bearings in two opposite sides and the 90 field magnets attached to the other two opposite sides, the four sides being integral and continuous throughout and having a web connecting the edges of said four sides.

5. In a signal of the class described, the 95 combination with the diaphragm, of a support therefor, means for vibrating the diaphragm comprising an electrical motor, said motor having a frame formed of a single sheet of metal stamping of rectangular 100 shape with the four sides thereof integral and continuous throughout, bearings for the motor shaft in two of said sides, field magnets attached to the other two sides and a fifth side transverse of the plane of the 105 other four sides and integral therewith.

6. In a signal of the class described, the 110 combination with the diaphragm of means for vibrating the diaphragm comprising an electric motor, said motor having a frame 115 consisting of a single piece of drawn sheet metal of rectangular cross section and with a web or bottom piece integral with the four sides, a motor shaft bearing in one of said four sides, the opposite side having a hole of larger diameter than the motor shaft and an extra piece carrying the other motor shaft bearing attached to said last mentioned side with the bearing in line with the hole, whereby the motor may be taken down by 120 detaching the said piece from the frame.

In testimony whereof I affix my signature.

EMANUEL AUFIERO.
